W. G. KENDALL

COMPACT HOLDER

Filed July 20, 1926

Patented May 3, 1927.

1,626,613

UNITED STATES PATENT OFFICE.

WILLIAM G. KENDALL, OF NEWARK, NEW JERSEY.

COMPACT HOLDER.

Application filed July 20, 1926. Serial No. 123,614.

This invention relates to improvements in compact holders. One of the objects thereof is to provide a novel form of ejecting means by means of which compacts may be 5 readily replaced with a minimum of effort. Another object of this invention is to provide a compact ejector within the compact holder which may be operated by a button on the outside of the holder.

10 Another object of this invention is to provide a novel form of double mirror for the cover of the holder, which will be hereafter more fully described.

Additional objects of the invention will 15 be apparent from the specification and drawings in which—

Fig. 1 is a horizontal section of my improved compact holder.

Fig. 2 is a sectional and enlarged view 20 showing the ejector mechanism in operation.

Fig. 3 is a horizontal section of the bottom of the holder showing details of the ejector mechanism.

Fig. 4 is a sectional view along the line 25 4—4 of Fig. 3.

Fig. 5 is a perspective view of the novel form of mirror employed showing the side of the mirror exposed on the outside of the cover.

30 Fig. 6 is another view of the cover of the holder showing the same mirror from the inside of the cover.

10 is a metal box of conventional form to which is attached the cover 11 having the 35 mirror 12 seated therein. The mirror 12 is a metal disk having a reflecting or mirror surface on both sides. It is held in the cover by means of the concave ring-shaped flange 13 and the independent resilient 40 annular member 14, the mirror being seated in the inner edge of the ring 14. The outer edge of the resilient ring 14 is laterally curved and is held by frictional engagement 45 in the depression of the ring-shaped member or flange 13. As shown in Fig. 1, the lateral contour of the flange 13 is angular and said flange is provided with a reentrant wall. Hence, when the periphery of the holding 50 ring 14 is snapped into position, the said ring is held very securely and cannot be removed save by the use of force, which would deform the shape of the edge of the said ring.

55 15 is the compact or rouge tray of conventional type. This pad 15 contains the

cosmetic 15. This tray rests upon the spring 17 made of a single narrow metallic ribbon resting upon the bottom 16 of the holder 10. The compact pad or tray 15 is confined within a metallic and elastic retaining ring fully illustrated in Fig. 4, having prongs 22 inwardly directed and normally engaging the sides of the rouge tray 15. The retaining ring R has a portion thereof shaped to form a leaf spring 18 which is actuated by the button 20 in its upper portion to permit the release of the cover 11 to permit the cover to be opened. Said retaining ring also has a lower spring portion or member 19 which is normally in 70 engagement with the ribbon spring 17 so as to permit the ejection of the tray 15 by the pressure of the finger upon button 21, as is fully illustrated in Fig. 2 of the drawing. The button 20 passes through an opening in the top portion of the wall of the box so that when it is pushed inwardly it forces the spring member 18 inwardly to release the cover. The button 21 is slidably located 75 in an opening at the bottom portion of the wall of the box so that when the said button 21 is pushed inwardly it forces the spring member 19 inwardly. When the spring member 19 is pushed inwardly, it contacts with and inwardly forces the adjacent end 80 of the spring member 17. This increases the curvature of the arched portion of the spring member 17 so that it moves or ejects the compact tray from the normal position shown in Fig. 1.

The cover 11 has a hinge member 10' integral therewith which is bent over and in engagement with extensions struck up from the body of the holder 10 along the line of the flange 24 so that no external means are 95 necessary to form a hinge for said holder, the hinge being formed from portions of the body of the cover and of the holder itself, as illustrated in Fig. 2.

It is obvious that pressure upon the button 21 by the finger F has a tendency to bend the spring 17 and raise the central portion thereof so that the tray 15 is raised from the body of the holder and can be readily grasped by the hand. The end of the 105 ejector spring 17 adjacent the associated spring member 19 is slidably, so that when spring member 19 is forced inwardly by button 21, the curvature of the ejector spring 17 is increased, which forces the tray 15 up- 110

wardly and releases it from prongs 22. A new compact tray may be readily put into the holder by pressing on the top of the tray as the form of the prongs 22 is such as to allow the tray to slip past said prongs, the periphery of the tray being normally held in engagement with said prongs. It is obvious that a device of maximum simplicity is provided because the retaining ring R which is made of resilient metal, surrounds the tray and because the resilient metal of which this ring is made, is cut and shaped to provide the prongs 22 for holding the tray 15 in position, and to also provide spring members 18 and 19 for respectively acting as a latch to hold the cover in position, and means for bending the ejector spring 17. As shown in Fig. 1, the top of the latch spring member 18 is adapted to fit over an inwardly directed shoulder of the cover 11.

I have shown a preferred embodiment of my invention, but it is clear that numerous changes and omissions could be made without departing from its spirit.

Having fully described my invention, what I claim is:—

1. A compact holder comprising a receptacle, a compact tray located in said receptacle, an ejector member located underneath the bottom of the said tray and adapted to move the tray upwardly upon actuation of said ejector member, a ring surrounding the said tray and adapted to hold it in proper position, and a spring member connected to the said ring and adapted to actuate the ejector member.

2. A compact holder comprising a receptacle, a compact tray located in said receptacle, an ejector member located underneath the bottom of the said tray and adapted to move the tray upwardly upon actuation thereof, a ring having a portion made of resilient metal and inwardly movable to provide a resilient spring member, the said spring member being adapted to contact with and to actuate the said ejector member.

3. A compact holder comprising a receptacle, a compact tray located in the said receptacle, an ejector member comprising a curved blade spring and located underneath the bottom of the said compact tray and adapted to move the tray upwardly when the curvature thereof is increased, a ring having a portion made of resilient metal

and inwardly movable to provide a resilient spring member, the said spring member being adapted to contact with and to actuate the said ejector member.

4. A compact holder comprising a receptacle having a cover, a compact tray located within the said receptacle, an ejector member located underneath said tray, said ejector member being adapted to move said tray upwardly upon actuation thereof, and a ring made of resilient metal and surrounding the said compact tray, a portion of said ring being cut out and shaped to provide a spring member closely adjacent to and adapted to contact with and actuate the ejector upon inner movement of said spring member, another portion of said ring being cut out and shaped to provide a spring member which is located at the top of the tray and adapted to releasably hold the cover of the receptacle in closed position.

5. A receptacle for compacts or the like having a cover provided with an opening at the top thereof, a mirror located directly adjacent the opening in the said cover and abutting the underside of the wall of said opening, the diameter of the mirror device being greater than the diameter of the opening in the said cover, the inner periphery of the said cover adjacent the said opening having an angular contour so as to provide an inwardly tapered portion and a holding ring for said mirror having a laterally curved periphery adapted to frictionally engage the inwardly tapered portion of the cover.

6. A receptacle for compacts and the like having a cover provided with an opening therein, the inner periphery of the said cover adjacent the said opening being formed with a re-entrant angle, and a mirror device mounted in a holding ring and located upon the underside of the said cover, the periphery of the said holding ring being laterally curved and yieldable, the edge of the said holding ring being seated upon the upper wall of the said re-entrant angle.

7. A receptacle for compacts or the like having a cover, said cover being provided with a re-entrant angle adjacent the outer edge thereof, and a mirror held in a ring and located at the underside of the said opening, the said ring resting upon the upper wall of the said re-entrant angle.

In testimony whereof I affix my signature.
WILLIAM G. KENDALL.
